UNITED STATES PATENT OFFICE.

ERNST NOLLE, OF WEISSENFELS-ON-THE-SAALE, GERMANY.

CHAIN.

No. 797,310.

Specification of Letters Patent.

Patented Aug. 15, 1905.

Application filed November 2, 1903. Serial No. 179,572.

To all whom it may concern:

Be it known that I, ERNST NOLLE, a subject of the King of Prussia, German Emperor, and a resident of Weissenfels-on-the-Saale, in the Province of Saxony, German Empire, have invented certain new and useful Improvements in Chains, of which the following is an exact specification.

My invention relates to improvements in chains, and more especially to the construction of chain-links consisting of a wire the ends of which are bent inward so as to form a closed loop.

According to my invention the extremities of the wire ends are bent so as to form a hook and catch and grip one above the other or embrace each other. Thereby the durability of the link and resistance against tension and traction is considerably increased.

In order to make my invention more clear, I refer to the accompanying drawings, in which—

Figures 1 and 2 are different side views of part of a chain constructed according to my invention. Fig. 3 is a section on line A B of Fig. 1. Figs. 4 and 5 are side views of a modified construction. Fig. 6 is a section on line C D of Fig. 4.

In the construction shown in Figs. 1 to 3, *a* is a wire bent so as to form a chain-link. The ends *b* and *c* of the wire are bent toward the

inside of the link so as to form a loop of a circular or similar form. The extremity of the end *c* is bent horizontally, and the extremity of the end *b* is bent somewhat downward, so that the extremities catch one another, thereby obtaining a chain-link which offers great resistance against being deformed.

In the modification shown in Figs. 4 to 6 the extremities of the ends *b* and *c* are twisted one around the other, as may be seen from the section Fig. 6. This construction has the advantage that the ends *b* and *c* cannot be so easily removed one from the other in the cross-direction.

Having thus fully described the nature of my invention, what I desire to secure by Letters Patent of the United States is—

A chain-link consisting of a wire, the ends of which are bent inward so as to form a closed loop, the extremities of the ends being twisted around each other and bent so as to form hooks which catch one another, substantially as described and for the purpose set forth.

In testimony whereof I have signed my name to this specification in the presence of two subscribing witnesses.

ERNST NOLLE.
